CARBURETOR METERING DEVICE

Herbert A. Woods, St. Louis, Mo., assignor to
 Carter Carburetor Corporation, St. Louis, Mo.,
 a corporation of Delaware

Application October 16, 1942, Serial No. 462,235

3 Claims. (Cl. 261—44)

This invention relates to carburetors for internal combustion engines and consists particularly in novel means for metering the fuel supplied by the carburetor.

In the usual form of automotive carburetor, liquid fuel is drawn from a constant level chamber through a nozzle and is mixed with air in the carburetor barrel or induction conduit to form the combustible mixture. The liquid fuel is metered through a metering restriction located at the base of the fuel nozzle and submerged in the fuel bowl. As the carburetor is heated, this restriction may be obstructed by fuel bubbles and, furthermore, the more or less segregated body of fuel in the main nozzle passage is susceptible to boiling, particularly after the engine has stopped, which causes liquid fuel to be spilled into the carburetor and intake manifold. This condition, known in the industry as "percolation" results in hard starting until such excess fuel evaporates or is carried from the manifold.

It is an object of the present invention, accordingly, to provide a carburetor in which the main fuel passages have substantially unrestricted communication with the fuel bowl and the metering of fuel is effected at the discharge end of the nozzle. Another object is to provide for metering fuel at the discharge end of the main fuel nozzle without, at the same time, appreciably varying the main supply of air through the carburetor.

These objects and other more detailed objects hereafter appearing are attained substantially by the device illustrated in the accompanying drawing in which

Fig. 1 is a sectional view of a carburetor embodying the novel fuel metering arrangement.

Fig. 2 is an outside elevation of the carburetor showing the means for operating the metering baffle.

Figs. 3 and 4 are enlarged, detail views showing the nozzle and fuel metering baffle in different positions.

Fig. 5 is a detail section taken on line 5—5 of Fig. 4.

The carburetor illustrated has a downdraft induction conduit including an air inlet horn 1 at the upper end controlled by a choker valve 2 which may be operated by any suitable manual or automatic means. At the lower end of the carburetor is an outlet portion 3 controlled by a butterfly type throttle valve 4 on a shaft 5. In the middle portion of the induction conduit are a pair of Venturi tubes 6 and 7. Adjacent the conduit is a bowl 8 enclosing the usual float 9 and a needle valve mechanism (not shown) for con-

trolling the normal level of fuel in the bowl. A main fuel nozzle 10 extends from the bowl to a point directly above the center of small venturi 6 and has a tip portion with a fuel outlet opening 11 facing generally across the direction of air flow, and an air inlet opening 12 facing against the air flow. The nozzle 10 is substantially unrestricted below the fuel level x—x.

Extending across the mixture conduit above the 10 Venturi tubes is a shaft 15 of generally circular cross section but having a central portion immediately adjacent the tip of nozzle 10 which is cut out, as at 16, so as to prevent an eccentric face 17 to the nozzle tip. On one end of shaft 15 outside the body of the carburetor there is secured a small arm 18 urged counterclockwise by a spring 23 and pinned to a cam follower link 19 which slides longitudinally in a guide 20. A follower roller 21 on the end of this link rides on 20 a cam 22 pivoted on the carburetor body.

The mechanism is arranged so that, as the throttle valve is moved, shaft 15 is rotated to vary the relationship of baffle surface 17 and the nozzle tip and thereby vary the effective suction on 25 the nozzle tip and, consequently, the rate of fuel discharge therefrom. The contour of cam 22 may be varied to provide for proper proportioning of the mixture at all throttle positions. Generally, this cam will be irregular in shape.

30 When the throttle is fully opened, the position of shaft 15 will be as in Fig. 3, with baffle face 17 substantially overlying and shielding the tip of the nozzle so that increased suction is applied to the nozzle outlet. This position, furthermore, 35 restricts the entry of air into inlet hole 12. The position of maximum leanness is shown in Fig. 1 in which the baffle face extends beneath the nozzle tip so as to increase the pressure on the nozzle outlet. The position of the baffle in Fig. 4 is intermediate. Cam 22 is shaped to provide for the 40 proper mixture enrichment as specified by the engine manufacturer and to obtain the maximum economy or power as determined by dynamometer tests. For instance, as the throttle is opened from 45 the position in Fig. 1, shaft 15 may remain stationary during the part throttle positions to provide best economy, and as the throttle approaches full open position, shaft 15 may rotate clockwise to provide a richer or power mixture.

50 The major portion of shaft 15 being of circular section, rotation of this shaft does not materially affect the total quantity of air flowing through the carburetor. The small cut-out portion 16 into which the nozzle tip extends replaces the 55 small primary venturi into which the nozzle ex-

tends in some carburetors. The carburetor may be provided with suitable auxiliary fuel systems such as the idling, accelerator, and step-up or economizer devices generally used.

The free communication between fuel bowl and the main nozzle insures that the temperature of fuel in the nozzle will be substantially the same as that of the larger body of fuel in the bowl and, consequently, the temperature of the nozzle fuel does not rise so rapidly after the engine has stopped and percolation is substantially reduced or eliminated. In any particular carburetor, baffle face 17 need not be adjustable to the extreme positions shown in the figures, these being merely illustrative of the possibilities of the device. Of course, the size of holes 11 and 12 in the nozzle tip may be varied to provide for the proper mixture proportions. The fuel metering arrangement is, accordingly, quite flexible and permits accurate calibration of the carburetor.

The arrangement may be modified in various respects as will occur to those skilled in the art and the exclusive use of all modifications as come within the scope of the appended claims is contemplated.

I claim:

1. In a carburetor air induction conduit, a constant level chamber, a fuel nozzle projecting into said conduit and having a tip portion above the fuel level, said portion having a discharge opening facing across the direction of air flow and an air inlet opening facing against the air flow, and a relatively small, generally cylindrical shaft extending across said conduit and having a deformed part immediately adjacent said tip por-

tion and presenting an eccentric face thereto, said baffle being rotatable to variably affect the air flow past said nozzle openings and, consequently, the metering of fuel through said nozzle.

2. In a carburetor, an induction conduit, a throttle, a fuel nozzle having an orifice opening into said conduit, a generally cylindrical shaft extending transversely into said conduit with its axis close to said orifice and having a cut-out part providing a face substantially on a chord of the shaft immediately confronting said orifice, and means to rotate said shaft to alter the position of said face relative to said opening and thereby affect the functioning thereof, the diameter of said shaft being substantially less than that of said conduit and said face extending only the width of said nozzle so that only the air flow substantially in line with said opening is affected by movements of said shaft.
3. In a carburetor, an induction conduit, a throttle, a venturi, a fuel nozzle having an orifice arranged to discharge fuel into said conduit, a shaft extending across said conduit, said shaft having a portion cut-out to form an eccentric face immediately adjacent said fuel outlet opening, and means operable by movement of said throttle to rotate said shaft to variably divert the air flow away from said nozzle and thereby affect the nozzle fuel discharge, the eccentric face of said shaft extending only substantially the width of said nozzle so that rotation of said shaft does not substantially affect the total air flow through said conduit.
